UNITED STATES PATENT OFFICE.

WILLIAM D. HOTT, OF LOY'S SHOP, NORTH CAROLINA.

RIDING-PLOW.

SPECIFICATION forming part of Letters Patent No. 517,923, dated April 10, 1894.

Application filed April 5, 1893. Serial No. 469,117. (No model.)

To all whom it may concern:

Be it known that I, WILLIAM D. HOTT, a citizen of the United States, residing at Loy's Shop, in the county of Alamance and State 5 of North Carolina, have invented a new and useful Riding-Plow, of which the following is a specification.

My invention relates to improvements in plows, and more especially to that class known 10 as riding or sulky-plows, wherein the same is mounted upon a pair of sulky wheels, the plow being carried by the intermediate axle.

The objects of my invention are to produce a plow of this class adapted to be used in connection 15 with various kinds of plow-shares, and to be so constructed as that the operator or driver mounted thereon may without leaving his seat raise and lower the plow thereby adapting it to run shallow or deep and raise 20 or lower the point or give it any other inclination or position that may be desired, and accomplish the same through the medium of a simple system of levers.

With these and other objects in view the 25 invention consists in certain features of construction hereinafter specified and particularly pointed out in the claims.

Referring to the drawings:—Figure 1 is a perspective view of a sulky-plow embodying 30 my invention. Fig. 2 is a vertical longitudinal sectional view, the plow being shown elevated out of operative position, as when traveling to and from the field of operation or turning at the end of a furrow. Fig. 3 is a 35 similar view, the plow being lowered to an operative position.

Like letters of reference indicate like parts in all the figures of the drawings.

In the construction of the plow an axle F 40 is employed, the same having one end cranked and terminating in bearings F' for the accommodation of the ground-wheels F². A longitudinal and centrally located beam A is supported upon and suitably secured to the center of the axle, and said beam is reduced at a point beyond the ground wheels forming a draft-tongue A', and at opposite sides of the axle provided with front and rear vertical mortises A² and A², respectively. A U-shaped 45 bracing-bail A⁴, is secured at its center to the upper side of the beam and is dropped at opposite sides thereof, as shown, and at its ends

extends to the rear and is secured to the axle F. Hounds A⁵ are secured to the beam A, diverge, and are secured to the bail at opposite 55 sides of the beam. The beam is provided with the usual draft-appliances that need no description.

In the mortises A² and A² there are located and adapted to move vertically and loosely a front and a rear bar D and D', respectively, the said bars being pivotally connected as at D² to the plow-carrying beam D³, whose ends project beyond the said vertical bars. The front end of the plow-carrying beam D³ is, 60 through the medium of a short chain D⁴, secured to the under side of the tongue, and the rear end of said plow-carrying beam is provided with a loose keeper D⁵. A hand-lever J is pivoted, as at J', in a recess formed 70 in the side and near the rear end of the main beam A, and the lower end of said lever engages loosely with the keeper D⁵ before mentioned.

A central standard B rises from the beam A, and in front and in rear of the same shorter standards C and C' rise. Upon the standards C and C' are pivoted or fulcrumed, as at C², a pair of levers designated as E and E', respectively, the latter extending forward 80 and terminating in a handle. The first mentioned lever E is pivotally connected to a short link G having a series of holes, through any one of which a pin may be removably passed for connecting it adjustably to a hand-lever G', which is fulcrumed as at G² upon the upper end of the central standard B and extends forward terminating in a suitable handle at the side of the lever E'.

A seat standard H rises from the axle and 90 supports a seat H' for the accommodation of the driver or operator.

A plow standard I is bolted securely to the plow-carrying beam D³, and to the same may be fastened any suitable style or pattern of 95 plow I', through the medium of the heel-bolt I². If desired double-shovels, scrapers, or any other plow may be employed.

It will be seen that the axle, by reason of the same being cranked at one side only, is 100 inclined, or in other words, it declines away from the moldboard-side of the plow, and hence it offers a resistance to the side pressure of the soil against the moldboard as the

furrow is formed, and the plow is therefore more apt to maintain a proper alignment and produce uniform, straight, parallel furrows. Between the two levers E' and G' a notched locking-standard G³ may be located, to which these levers may be secured.

The operation of the plow will be readily understood from the foregoing description in connection with the drawings, but in order to 10 avoid mistake I will briefly outline the same as follows: In order to adjust the plow to run shallow the lever E' is depressed so as to raise the plow as an entirety. This lever, it will be seen, operating upon its fulcrum C², causes the rear bar D' to move vertically, and as it moves vertically the plow-carrying beam D³, moving on its front fulcrum D², raises the plow a suitable distance, in which position it may be locked, where the ground is not stony, by engaging 15 the lever E' with the aforesaid locking-standard. When depressed by means of the lever E' its "suck," or more properly speaking, its inclination, is regulated by the raising and lowering of the levers G', and it will be seen that 20 the plow may be withdrawn through the medium of the lever J, if the point should become caught under a root or rock. While operating should the point meet with a hard substance the link G will permit it to yield 25 and thus avoid breakage.

I do not limit the details of the invention to those herein shown and described, but hold that I may vary the same to any extent and degree within the scope of the knowledge of 30 the skilled mechanic.

Having described my invention, what I claim is—

1. In a sulky plow, the combination with the axle, the ground-wheels, the main beam, 40 the lower plow-carrying beam, and the vertically and longitudinally movable bars mounted in elongated mortises in the main beam and pivoted at their lower ends to the opposite sides of the center of the plow-carrying 45 beam, levers for raising and lowering said bars, and a rear lever pivoted on the main

beam and loosely connected to the rear end of the plow-carrying beam, substantially as specified.

2. In a sulky plow, the combination with the axle, the ground-wheels, the main beam terminating in a draft-pole and provided with mortises, of the lower plow-carrying beam provided at its rear end with a keeper, a lever fulcrumed on the rear end of the main beam and engaging the keeper, a draft-chain between the under side of the pole and the front end of the plow-carrying beam, vertical bars arranged in mortises in the main beam and pivoted at their lower ends to the plow-carrying beam, the central standard B and the side standards C and C' arranged on the main beam, the lever E fulcrumed on the standard C and pivotally connected at its front end to the upper end of the front vertical bar, the lever G' fulcrumed on the standard B and terminating at its front end in a handle, a link G connecting the rear ends of the levers G' and E, and the lever E' fulcrumed on the standard C' terminating at its front end in a handle, and having its rear end pivoted to the rear vertical bar G', substantially as specified.

3. In a sulky plow, the combination with an axle and its ground-wheels, and a main beam supported on the axle, of a plow-carrying beam arranged below the main beam, vertically movable bars loosely supported upon the main beam and pivotally connected at their lower ends to the plow-carrying beam, 80 levers fulcrumed above the main beam and connected to the upper ends of the bars, and a lever pivoted to the beam and loosely connected at its lower end to the plow-carrying beam, substantially as specified.

In testimony that I claim the foregoing as my own I have hereto affixed my signature in the presence of two witnesses.

WILLIAM D. HOTT.
